UNITED STATES PATENT OFFICE.

ANDREW F. FORD, OF PORTLAND, OREGON.

FRICITION-BRAKE FOR DIFFERENTIALS.

1,358,434.

Specification of Letters Patent. Patented Nov. 9, 1920.

Application filed August 30, 1919. Serial No. 320,919.

To all whom it may concern:

Be it known that I, ANDREW F. FORD, a citizen of the United States, residing at Portland, in the county of Multnomah and 5 State of Oregon, have invented new and useful Friction-Brakes for Differentials, of which the following is a specification.

My invention refers more particularly to that class of inventions called bevel gear 10 differentials such as are in common use on automobiles.

The object of my invention is to provide an exceedingly simple and efficient means for preventing undue slippage on one of the 15 rear wheels due to unequal weight on same, or differences in road friction.

To accomplish this result I have constructed a device which is illustrated in the accompanying drawings and described in the 20 specification following.

Referring to the drawing. Figure 1 is an end elevation of the device as used between the spiral gears in a differential; Fig. 2 is a front elevation of Fig. 1; Fig. 3 25 is an elevation looking from the outside of the device; Fig. 4 is an elevation showing the reverse side of Fig. 3; Fig. 5 shows the two halves of the device assembled. It will be noticed in Figs. 1 and 2 that the differential parts are shown in phantom, and in 30 Figs. 3, 4 and 5 is illustrated the device itself.

Similar letters and numbers of reference refer to the same or similar parts throughout the several views.

Referring in detail to the drawing, A¹ are the usual bevel gears of a differential between which is interposed the three-legged spider A² upon which are commonly mounted 40 bevel pinions A³, which I have omitted from Fig. 1 for the sake of clearness.

My device consists of the two irregular disks F illustrated in Figs. 3, 4 and 5 which are supplied with a circular hole F¹, around 45 which is formed an annular ring F², and spaced equi-distant on its circumference are the recesses F³ which are shaped to receive the bevel pinions A³ and to permit same to 50 rotate in the same manner and meshing with the same bevel gears that they did when mounted on the spider A¹. Mid-way between the recesses F³ are the counter bore recesses F⁴ which are adapted to receive the legs of the spider A².

55 It will be noticed in Fig. 1 that the out-

ward portion of the counter bore F⁴ is made slightly elliptical and its purpose is intended to produce a more decided lateral thrust outwardly against the pair of disks F, thereby forcing the surfaces F⁵ and F⁶ 60 against the face of the teeth in the bevel gears A¹ producing a frictional braking effect on the same which tends to reestablish the balance between the two wheels of the automobile and prevent the undesirable 65 spinning.

It is evident that no change is made in the parts already on the car except to remove the bevel pinions A³ from the spider A² and insert them into the recesses F³. 70 Owing to the fact that these pinions A³ do not rotate at all while the vehicle is traveling in a straight line and only rotate slightly when a curve is being made, it is apparent that the amount of wear on the 75 gear teeth, or the disks themselves will be very slight—in fact, less than it would be were the pinions obliged to race around the gears during the slipping of one of the wheels.

I have shown in the drawing the three-legged type of spider, but it is evident that this principle may be adopted where any number of pinions are used without departing from the spirit of my invention. 80

It will be seen upon examination of the drawing that the friction of the disks is not merely against the gear teeth but against every portion of the gear from the central shaft to the outside of the gear teeth, which 90 means that all of the surfaces F⁵ and F⁶ become friction surfaces, and a slight amount of wear will cause the entire surfaces F⁵ and F⁶ to seat themselves against the gears, merely prolonging the life of the 95 device.

While I have thus illustrated and described my invention it is not my desire to limit myself to this precise form of invention or method of application of same, but 100 intend that it shall cover all forms and modifications that fall fairly within the appended claims.

What I claim as new and desire to protect by Letters Patent of the United States, is: 105

1. A friction brake for bevel gear differentials consisting of a pair of disks arranged to occupy all of the space between the bevel gears not occupied by the spider and pinions, and having recesses adapted to 110

receive said bevel pinions which have previously been removed from the spider of the differential.

2. A friction brake for bevel gear differentials consisting of a pair of disks arranged to occupy all of the space between the bevel gears in a differential in a manner that the separation of said disks will produce a friction on the gears over their entire surface from the central shaft to the outside of the gear and having recesses formed between same to receive the legs of

the spider from which the pinions have been removed, said recesses being made slightly elliptical in a manner to serve as wedging surfaces for the legs of the differential spider, said disks being relieved to admit the rib of said spider and having other recesses formed between the spider leg recesses which are adapted to contain the bevel pinions and permit same to rotate therein in mesh with the bevel gears. 15 20
